[57] **CLAIM**

The ornamental design for a loudspeaker, as shown and
described.

DESCRIPTION

FIG. 1 is a front and right side perspective view of a
loudspeaker showing my new design;

FIG. 2 is a front and right side perspective view thereof
with the covers removed;

FIG. 3 is a left side elevational view thereof, the right
side being a mirror image;

FIG. 4 is a top plan view thereof; and

FIG. 5 is a bottom plan view thereof.

The rear of the loudspeaker is plane and unornamented.
